UNITED STATES PATENT OFFICE

ERNEST J. NEWCOMER, OF BALTIMORE, MARYLAND

FLOOR-POLISHING MACHINE

Application filed December 14, 1926. Serial No. 154,729.

This invention relates to an improvement in floor polishing machines.

The object of the invention is to provide a machine of this character of an improved construction for waxing, polishing or scrubbing a floor without danger of splashing water, dust, dirt or wax into the gears of the machine.

A further object of the invention is to provide for an even distribution of the stresses over the various parts of the machine, and to enclose and protect the reduction gearing so that it is housed in the most confined and efficient manner.

With these objects in view, the machine is constructed of a brush gear housing having an integral dropped partition in the center which supports the main shaft, and this dropped partition co-operates with a gear case cover seated upon the upper peripheral edges thereof to form a compartment for the reduction-gears of the machine. The driving-motor is mounted above the gear-case cover. An internal ring-gear is secured in a fixed position in the brush gear housing in position to mesh with the brush-gears mounted on brush-shafts, which are in turn supported by an enlarged supporting-plate carried on the main shaft, and which plate extends outwardly substantially to the outer edge of the brush-gear housing to prevent any water, wax, or dust from being thrown into the upper portion of the housing, where it might interfere with the operation of the brush and ring-gears.

The accompanying drawing is a vertical sectional view through a machine constructed in accordance with this invention.

A brush gear casing 1 is adapted to enclose and house the main portions of the operating parts of the machine, and is provided with upstanding lugs 2 to which the handle-yoke 3 is pivotally mounted for moving the machine over the surface to be scrubbed, waxed or polished.

The brush-gear housing 1 is provided with an upstanding annular ridge 4 upon the top 5 thereof, upon which ridge a gear case cover 6 is seated. A motor housing 7 is mounted upon the cover 6, and these parts

are secured to the ridge 4 by means of the motor-housing screws 8 which extend through the flange on the housing 7 and the cover 6 and into the ridge 4. A partition 9 extends downwardly at an angle of substantially 45° from the ridge 4 of the brush-gear housing, and is integral with this ridge and the housing. The partition 9 terminates at its lower end in an enlarged bearing 10 formed integral therewith; and on one side of this bearing 10 is a smaller bearing 11.

As shown in the drawings, the partition 9 is substantially cup-shaped, and forms a chamber 12 within the top of the brush-gear housing for receiving the reduction-gears of the machine.

The numeral 13 indicates the armature-shaft of the motor, which also carries the fan 14 thereof, and this armature-shaft is mounted in ball-bearings 15 carried by the gear case cover 6. A pinion 16 is fixed on the armature-shaft 13, and meshes with a reduction-gear 17 fixed on the reduction-shaft 18 mounted at its upper end in a bearing 19, and at its lower end in the bearing 11. A reduction-pinion 20 is also fixed on the reduction-shaft 18 and meshes with a driving gear 21 fixed on a main-shaft 22. This main shaft 22 is mounted in ball-bearings 23 mounted in the main bearing 10 formed in the partition 9.

A supporting-plate 24 is carried on the lower end of the main shaft 22, and is of a diameter only slightly less than that of the brush gear housing 1, so as to lie immediately inside the inner wall of this housing, substantially to close the space thereabove and form a partition between the upper and lower portions of the housing to prevent any water, wax or dust from being thrown into the upper portion thereof. This supporting-plate is provided with integral hubs 25 forming bearings for brush-shafts 26, which support brushes 27 on the lower ends thereof. The upper ends of these brush-shafts above the supporting-plate 24 carry brush-gears 28, which mesh with a ring-gear 29 secured by screws 30 on an internal flange 31 formed in the brush gear housing 1. The brush gear housing prefer-

ably extends below the upper ends of the brushes or other rubbing elements which might be secured on the shafts 26, in order to house and enclose these rubbing elements to prevent the scattering of any liquid or wax centrifugal force, and to prevent its being thrown out over the floor to any substantial degree.

The chamber 12 for the reduction-gears is preferably packed with grease in order to keep these gears thoroughly lubricated, and this initial packing is usually sufficient for the entire life of the machine.

As the motor is operated, its rotary movement is transmitted to the main shaft 22 through pinion 16, reduction-gear 17, reduction-pinion 20, and drivegear 21, which rotates the supporting-plate 24, causing the gears 28 to turn within the ring-gear 29, thus giving rotary motion to the rubbing elements 27 for scrubbing, waxing or polishing the floor. The supporting-plate 24 prevents any injury to the gearing or bearings by keeping all dust, wax, or liquid out of the upper portion of the brush gear housing 1, thus keeping the machine in better operating condition.

The peculiar construction of the partition 9, closed at its upper peripheral edge by the gear case cover 6, provides a compact enclosure for the reduction gearing, keeping all foreign particles therefrom, and insuring the perfect operation of the machine, as well as providing a compact and light construction, thus making it easy to handle and operate.

I claim:

1. In a machine of the character described, the combination of an outer casing, a motor supported thereby, rubbing members, shafts on which said rubbing members are secured, a fixed-gear mounted at the outer portion of the outer casing, gears fixed on the shafts and meshing with said fixed gear, a supporting plate carrying said shafts and extending outwardly beyond the shafts substantially to the edge of said outer casing forming a guard, and means for turning the supporting plate from the motor.
2. In a machine of the character described, the combination of an outer casing having a peripheral ridge formed on the top portion thereof, said top portion having a partition extending downwardly from the ridge at an angle of approximately 45°, forming a cup-shaped chamber in the top of the casing, said partition being integral with the casing, a main shaft mounted approximately centrally of the partition, rubbing elements connected with the main shaft, a cover-plate mounted on the ridge and approximately closing the top of the chamber, a motor mounted upon the casing above the chamber, and reduction-gearing mounted in the cham-

ber and connecting the motor with the main shaft.

3. In a machine of the character described, the combination of an outer casing, a gear fixed to the outer casing approximately at the periphery thereof, a supporting plate rotatably mounted in the casing and extending approximately to the outer edge thereof, rubbing elements carried by said plate, pinions operatively connected with the rubbing elements and on the opposite side of the plate therefrom, said pinions being meshed with the fixed gear, and driving means for the plate.

In testimony whereof I affix my signature. 80
ERNEST J. NEWCOMER.
